CLAIM

The ornamental design for a cabinet, as shown and described.

DESCRIPTION

FIG. 1 is a front, right, upper perspective view of a cabinet embodying my new design;

FIG. 2 is a front elevational view thereof;

FIG. 3 is a top plan view thereof;

FIG. 4 is a right side elevational view thereof;

FIG. 5 is a left side elevational view thereof; and,

FIG. 6 is a rear elevational view thereof.

The broken lines shown in FIGS. 1-6 are for illustrative purposes only and form no part of the claimed design. The broken away portions shown in FIGS. 1-6 represent indeterminate width of the claimed design.
